UNITED STATES PATENT OFFICE.

PAUL SEEHAUS, OF NEW YORK, N. Y.

DESIGN FOR A CANE OR UMBRELLA HANDLE.

SPECIFICATION forming part of Design No. 16,796, dated July 13, 1886.

Application filed May 20, 1886. Serial No. 202,812. Term of patent 14 years.

To all whom it may concern:

Be it known that I, PAUL SEEHAUS, of the city, county, and State of New York, have invented a new and original Design for Cane and Umbrella Handles, of which the following is a full, clear, and exact description, reference being had to the accompanying drawings, making part of this specification, in which—

Figure 1 is a side view of my new design for cane and umbrella handles, and Fig. 2 is a cross-section on the line *x-x*, Fig. 1.

Similar letters of reference indicate corresponding parts.

The leading feature of my design consists of bars of music in relief on the surface of the cane-handle, and space reserved on the surface of the handle for the purpose of suitable word inscriptions.

A is the cane or umbrella handle; B, the neck of the same; C, bars of music in relief on the surface of the handle, and D the space below the bars of music on the surface of the handle, for the purpose of receiving suitable word inscriptions.

Having thus described my design, I claim as new and desire to secure by Letters Patent—

1. The design, substantially as herein shown and described, for a cane or umbrella handle, the same consisting of a handle having bars of music in relief on its surface.

2. The design for a cane or umbrella handle, substantially as herein shown and described, the same consisting of a handle having bars of music in relief on its surface, and a space for suitable word inscriptions below the bars of music.

3. The design, substantially as herein shown and described, for a cane or umbrella handle, the same consisting of a handle having bars of music in relief on the handle and neck, and a space for the purpose of receiving suitable word inscriptions below the bars of music on the handle and neck.

In testimony that I claim the foregoing as my invention I have signed it this 18th day of May, 1886.

PAUL SEEHAUS.
